UNITED STATES PATENT OFFICE.

JESSE M. PAYNE, OF PHOENIX, ALABAMA.

DYEING-MACHINE.

996,514.

Specification of Letters Patent. Patented June 27, 1911.

Application filed October 27, 1910. Serial No. 589,416.

To all whom it may concern:

Be it known that I, JESSE M. PAYNE, a citizen of the United States, residing at Phoenix city, in the county of Lee and State 5 of Alabama, have invented certain new and useful Improvements in Dyeing-Machines; and I do declare the following to be a full, clear, and exact description of the invention, such as will enable others skilled in the art 10 to which it appertains to make and use the same.

This invention relates to improvements in dyeing machines.

The invention consists in the construction 15 and arrangement of parts as will be herein-after described and particularly pointed out in the claim.

In the accompanying drawings: Figure 1 is a central vertical longitudinal section 20 through my improved dyeing machine and the beam operating mechanism; Fig. 2 is a similar view taken at right angles thereto and on the line 2—2 of Fig. 1; Fig. 3 is a similar view on the line 3—3 of Fig. 1; Fig. 25 4 is a similar view on the line 4—4 showing the beam operating mechanism. Fig. 5 is a cross sectional view on the line 5—5 of Fig. 1.

Referring more particularly to the drawings, 1 denotes a large outer tank which is adapted to contain dye and in which the dye is heated. Arranged in the tank 1 is a dyeing tank 2 in which is revolubly mounted a 30 yarn holding beam or reel 3. The beam or reel 3 comprises a centrally disposed shaft 4, on which and spaced a suitable distance apart are circular heads or disks 5 and 6. On the inner sides of the disks 5 and 6 are formed annular ribs or flanges 7 in which 35 are formed a series of triangular seats or notches 8 with which are engaged the opposite ends of a series of cross bars or slats 9 upon which the yarn to be dyed is wound. The slats 8 are spaced a suitable distance 40 apart to permit the dye to flow freely through the same and through the yarn wound thereon.

The disks or heads 5 and 6 are held in position on the shaft 4 by nuts 10 and on the 45 outer side of the head 6 is formed an annular concentric flange 11 which is threaded interiorly as shown. The interiorly threaded flange 11 is adapted to be screwed into engagement with the enlarged threaded inner end 12 of a combined tubular reel or beam operating shaft and dye injecting nozzle.

zle 13 through which dye is discharged into the reel or beam while the same is being revolved. The enlarged inner end 12 of the shaft 13 has formed thereon an annular radially projecting stop flange 14 in which is arranged an annular gasket or packing ring 15 against which the outer end of the flange 11 on the head 6 of the reel is screwed thereby forming a fluid tight connection between these parts. In the discharge end of the shaft 13 is formed an apertured bearing bar or spider 16 with which the adjacent end of the shaft 4 is engaged, the opposite end of said shaft having a revoluble engagement with a bearing notch 17 formed in a supporting bar 18 arranged across the tank 2 and having its opposite ends engaged with a suitable supporting cleat 19 arranged on the adjacent side of the tank as shown.

The tubular shaft or nozzle 13 is revolvably supported at its inner end where it enters the tank 2 in a stuffing box 20 while the outer portion of the shaft or nozzle where the same passes through the side of the tank 1 is engaged with a stuffing box 21 arranged in and secured to said side of the tank 1 as shown. To the outer end of the shaft or nozzle 13 is connected a dye supply pipe 23 which may be connected with a suitable pumping mechanism (not shown) which is so arranged that after an air-tight lid or cover has been placed on the dye tank 2, by the manipulation of the proper valves or by reversing the pump, the dye liquor may be forced through the pipe 23 and the nozzle or shaft 13 outwardly through the reel of yarn into the tank 2, or may be driven in the reverse direction from the tank 2 through the reel and shaft back into the tank 1. The supply pipe 23 is connected to the end of the shaft 13 by a packing joint or union 24.

The shaft or nozzle 13 is revolved to impart the required rotary movement to the reel by means of a suitably driven worm shaft 25 which is revolubly mounted in bars 26 and is operatively engaged with a worm gear 27 fixedly mounted on the outer end of the shaft or nozzle 13. By thus constructing and arranging the reel operating mechanism the reel or beam may be revolved at the desired speed in the tank 2 at the same time the dye is being pumped through the nozzle and into the enlarged outer end thereof from whence it passes through an opening 28 formed in the head 6 and into the reel or beam. As clearly shown in Fig. 1 of the

drawings; the enlarged end or head 12 of the shaft 13 is formed with a continuous annular flaring funnel-shaped discharge open end leading to the concentric securing flange 11, whereby the dyeing liquid is freely and uninterruptedly directed to the material to be operated upon. After entering the reel or beam the dye passes out between the bars or slats 9 and through the 10 yarn wound thereon thus evenly dyeing the latter and preventing any settling of the dye at the lower part of the reel or beam.

It will be observed that in my present device, the driving shaft and nozzle is secured 15 directly to the drum or dyeing beam without the use of bolts so that these parts may be expeditiously attached and detached and the construction is such that the act of attaching the nozzle to the beam simultaneously 20 presses the packing against the flange on the beam evenly throughout its extent. The spider in the nozzle furnishes a support for the end of the shaft so that the weight of the beam and the yarn thereon 25 will not be thrown upon the threaded connection between the nozzle and the beam and, consequently, wear and loosening of that connection will not readily occur. It will also be noted that the enlarged end of 30 the nozzle fits closely within the central opening in the side of the tank so that the head of the beam is brought close to said side of the tank and a steady support for

the same is provided as well as an economy of space effected.

The dyeing liquor may be removed from the tank 2 by any suitable means, as by a pipe 30, with which will be combined a valve not necessary to be shown.

Having thus described my invention 40 what I claim is:

A dyeing apparatus comprising an inner and an outer tank, a shaft, a reel on the shaft consisting of flanged disks having spaced notches adapted to receive slats 45 therein, one of the disks having an annular interiorly screw threaded projecting concentric flange, a rotatable nozzle extending through the walls of the inner and outer tanks having a flaring screw threaded end 50 provided with a stop flange to connect with said concentric flange, said flaring end of said nozzle being spaced from said concentric flanged disk, a spider arranged within said nozzle having one end of said shaft 55 mounted therein and an opening in the concentric flanged disk providing communication between the interior of the reel and the nozzle.

In testimony whereof I have hereunto set 60 my hand in presence of two subscribing witnesses.

JESSE M. PAYNE.
